[57] CLAIM

The ornamental design for a handle for cooking utensil,
substantially as shown.

DESCRIPTION

FIG. 1 is a side elevational view of a handle for cooking
utensil showing my new design;

FIG. 2 is a top plan view thereof;

FIG. 3 is an end elevational view from the right of FIG.
1; and

FIG. 4 is an end elevational view from the left of FIG.
1.

The side and bottom opposite that shown respectively
in FIGS. 1 and 2 are similar thereto.
